2 Claims. (Cl. 70—364)

This invention concerns a key-operated lock.

According to the invention there is provided a key-operated lock comprising a rotatable barrel in a frame, said barrel containing a series of wards, each ward being received in one of a series of parallel guiding slots which extend diametrically across the barrel, said wards being spring-biased towards one or other of two diametrically opposite locking grooves in said frame such that, on removal of the key from the lock, the wards move to a locking position in which they engage one or other of the two diametrically opposite locking grooves, said wards being so shaped that they can be fitted into the guiding slots within the barrel either way round to co-operate with either one of the edges of the key used to open the lock.

According to one feature of this invention the barrel may comprise two parts which engage one another by way of a contact surface lying parallel with the longitudinal axis of the barrel and said guiding slots may be disposed in one of two parts forming the barrel, the slots opening onto the contact surface and having a rectilinear base parallel with the contact surface.

Very conveniently the guiding slots may widen out to provide grooves which are parallel with such slots, these grooves serving to house the springs which bias the wards towards their locking position. Each groove may serve to house a spring for biassing the appropriate ward towards the locking grooves. According to a still further feature of this invention each said spring may have one of its ends bearing against an abutment on its ward and may have its other end bearing against a bearing plate conveniently positioned transversely of the groove housing the spring.

Very desirably each said bearing plate may be positioned within a groove itself positioned transversely of the direction of movement of the wards. Preferably two grooves may be provided for receiving bearing plates, said grooves advantageously extending parallel with the diametric plane of the cylinder, but are offset one to each side thereof.

According to yet a further feature of this invention the or each groove for receiving the bearing plates may be shallower than the grooves that house the spring biassing the wards towards their locking position, said bearing plates conveniently having a central portion shaped to conform substantially with the cross-sectional shape of the grooves which house said springs. Desirably the two locking grooves in the frame may be slightly offset laterally from the diametric plane of the barrel and to the same side thereof to restrain the key from withdrawal from the lock except when the barrel is in the required angular position.

In order that the invention may be more readily understood one embodiment of the same will now be described by way of example with reference to the accompanying drawings in which:

FIGURE 1 is a longitudinal sectional view through the embodiment, taken along the line 1—1 of FIGURE 2,

FIGURE 2 is a sectional view perpendicular to the section in FIGURE 1 and taken along the line 2—2 thereof,

FIGURE 3 is a cross-sectional view on a reduced scale and taken along the line 3—3 of FIGURE 1,

FIGURE 4 is a fragmentary perspective view on an enlarged scale of a part of the lock,

FIGURE 5 is a plan view of a lock component,

FIGURE 6 is a cross-sectional view taken along the line 6—6 of FIGURE 2, and

FIGURE 7 is a plan view of an element used in an alternative arrangement.

The lock illustrated is of the double-barrel kind and comprises two opposite barrels 2, 2' which are disposed in a frame 1 and retained axially in said frame 1 by rings 3, and a key bit 4 rotatably mounted on the inner ends of the two barrels 2, 2' (FIGURE 1). The two barrels 2, 2' are identical and each comprise a two-element body in the form of a main element or part 5 having substantially circular terminal portions 5a, 5b interconnected by a central portion 5c which in cross-section resembles a segment of a circle, and an auxiliary element or part 6 which in shape resembles a segment of a cylinder and which is engaged in the main part 5. The two parts 5, 6 of each barrel are interconnected by a hollow screw 7 which has a slotted countersunk head 7a and a tailpiece 7b (FIGURE 2). The two parts 5, 6 form a substantially cylindrical assembly rotatable in the frame 1.

The key bit 4 is formed with a rectangular aperture 4a, and each of the two barrels 2, 2' comprises a U-shaped member 8 having a central part 8a adapted to engage in the aperture 4a so that the key bit 4 can rotate solidly with one or other of the barrels 2, 2'. One of the parallel arms of the U-members 8 is received in the hollow screw 7 of the corresponding barrel, and the other such arm is received in a parallel aperture 9 in the barrel part 5. Springs 10 disposed below the U-shaped members 8 tend to urge the same towards the key bit 4 (FIGURE 2).

The terminal portions 5a, 5b of the part 5, and the part 6, are pierced with an axial passage 11 in which the shank 12a of a flat key 12 can slide; in the drawings the key is shown introduced into the lock barrel 2. The key shank 12a is formed with a lateral groove 12b, and the passage 11a in the outer portion 5a of the part 5 has a matching rib 11b allowing the key to pass only in one direction. Key length is such that the key front end 12c co-operates with the U-shaped member 8 of the barrel in which the key is engaged to move the member 8 into engagement with the key bit 4 while disengaging the U-shaped member 8 of the other barrel from the key bit 4, in known manner.

The passages in the frame 1 which receive the barrels are each formed with two axial locking grooves 13, 14 which are diametrically opposite one another and which are engaged by the ends of wards to be described herein-after; the purpose of the wards is to prevent the barrels from being rotated by a key of the wrong shape.

The part 6 of each barrel is formed with seven guiding slots 15 which are equidistant from one another and which are disposed in planes perpendicular to the barrel axis A—A. The slots 15 open into the bottom of wider parallel grooves 16 in a flat contact surface 17 of the part 6, the surface 17 engaging with a corresponding contact surface of the part 5 (FIGURE 4). As can be seen in FIGURE 6, the base 18 of the slots 15 is parallel with the contact surface 17. The seven slots 15 serve to guide seven wards 19 which have one long straight side 20 in contact with the slot base 18, and a parallel side 21a, 21b in contact with the plane contact surface of the part 5.

Each ward 19 is formed with a recess 22 comprising a base part 23 which is disposed in the thin part 15 of the slot and through which the key shank 12a extends, the recess 22 also having an entry part 24 disposed in the wider groove 16 (FIGURES 4 and 6). One edge, 23a, of the recess 22 is adapted to cooperate with the key bottom edge 12d, while a spring 25 which is compressed between an edge 24a of the recess 22 and a bearing plate 26, tends to raise the ward 19 (FIGURE 6). When no key is inserted, the ward 19 is moved by the spring 25 into a top end position determined by an edge 24b of the recess 22 abutting the bottom surface of the bearing plate 26. In this position the ward end part 19a projects beyond the cylindrical outer surface of the barrel

and, by engaging in the locking groove 13, prevents the barrel from rotating.

In an alternative form of the ward which can be seen in FIGURE 7, the ward 19' can be formed with a central aperture 28 through which the key passes and which serves the same purpose as the part 23 of the recess 22, and with a recess 29 which serves the same purpose as the part 24 of the recess 22. The recess 29 and the aperture 28 are separated from one another by a continuous part 30 which considerably increases the mechanical strength of the ward. When the key moves in the barrel, the passage of a raised part of the key, such as the part 12e, lowers the ward 19', and the ward end part 19b is made to extend beyond the outside surface of the barrel and briefly penetrates into the groove 14. Since the locking grooves 13, 14 are slightly offset laterally to the right from the barrel axis B—B (FIGURE 6), the key can be withdrawn from the lock only when the barrel is in the angular position illustrated, in which position the barrel is locked immediately the key is withdrawn.

The bearing plate 25 is shown separately and in plan view in FIGURE 5. The plate 25 comprises a central part 26a of the same shape as the cross-section of the groove 16, and two lateral parts 26b which, as can be seen in FIGURE 4, are engaged in a longitudinal groove 27a in the plane surface 17 of the part 6, the groove 27a extending in a direction perpendicular to the slots 15, 16 (FIGURES 1 and 4).

The groove 27a which is shallower than the grooves 15 and which extends over the whole length of the part 6, is laterally offset from that axial plane of the barrel which is perpendicular to the contact surface 17. A second groove 27b identical to the groove 27a is disposed with the same offset but on the other side of such plane (FIGURES 1 and 4).

The wards 19 can be mounted reversed in the guiding slots 15 to co-operate with either of the key edges. For instance, the ward Z nearest the key bit 4 is adapted to co-operate with the left-hand edge E of the key (FIGURE 1), whereas the penultimate ward Y, which is the other way round as compared with the ward Z, is adapted to co-operate with the right-hand edge F of the key. As can be seen in FIGURE 4, the bearing plate 26z associated with the ward 19z is received in the groove 27a (FIGURE 4), whereas the plate 26y of the ward 19y disposed reversed is disposed in the groove 27b. In the lock illustrated in the drawings, the wards U, X, Z of the barrels are disposed in the same direction and co-operate with recesses in the key edge E, whereas the wards T, V, W, Y are disposed in the opposite way round to the wards U, X, Z and co-operate with the key edge F (FIGURE 1).

The lock illustrated has the following advantages:

The slots and grooves 13, 16, 27a, 27b in the part 6 open onto the contact surface 17 thereof and can be readily embodied since they extend right through the part 6. Also, since the wards 19 can be fitted to be moved in either direction, the number of possible combinations which can be provided by a given number of wards and a given number of ward heights is increased considerably. This increase in the possible number of combinations which can be provided is a great help in solving the particular problem of devising a series of locks associated with different individual keys, and yet enable skeleton keys

for all or groups of the locks to be made. In cases like this, the number of combinations which conventional barrel locks can provide is very soon exhausted, whereas with the lock according to the invention the fact that the wards can be reversed makes it unnecessary to provide extra baffles. Another advantage is that it is easy to fit the wards 19 and springs 25 in the barrel part 6, and all the moving parts are disposed within the barrels which can be completely assembled independently of the frame.

While I have disclosed two embodiments of the present invention, it is to be understood that these embodiments are given by example only and not in a limiting sense, the scope of the present invention being determined by the objects and the claims.

I claim:

1. A key-operated lock comprising a frame, structure on said frame defining a pair of substantially diametrically opposite locking grooves, a barrel rotatably housed in said frame, structure on the barrel defining a series of diametrically extending guiding slots, a series of wards for movement in said slots, and spring means adapted to bias said wards to a locking position in said locking grooves, said wards being so shaped that they can be fitted into the guiding slots within the barrel to move in one direction or in the reverse direction to cooperate with either one of the edges of the key used to open the lock, said barrel comprising two parts which engage one another by way of a contact surface lying parallel with the longitudinal axis of the barrel, and said guiding slots being disposed in one of the two said parts forming the barrel, said slots having a rectilinear base parallel with the contact surface, and the open part of the slots being adjacent the said contact surface.

2. A key-operated lock comprising a frame, structure on said frame defining a pair of substantially diametrically opposite locking grooves, a barrel rotatably housed in said frame, structure on the barrel defining a series of diametrically extending guiding slots, a series of wards for movement in said slots, a series of grooves defined by widened portions of said slots being provided, a series of springs being housed within said grooves to bias said wards towards said locking grooves, a bearing plate positioned transversely of each of the said grooves housing the said springs, such that each spring is positioned within its groove between its bearing plate and the ward which it is biasing towards a locking position, said grooves for receiving the bearing plates being shallower than the grooves which house the springs and said bearing plates having a central portion shaped to conform with the cross-sectional shape of the grooves which house said springs.
